UNITED STATES PATENT OFFICE.

HERBERT PEARCE AND JOHN ERNEST BILLINGTON, OF BROADHEATH, ENGLAND.

TYPOGRAPHICAL COMPOSING AND CASTING MACHINE.

941,384.

Specification of Letters Patent. Patented Nov. 30, 1909.

Application filed June 26, 1909. Serial No. 504,586.

To all whom it may concern:

Be it known that we, HERBERT PEARCE and JOHN ERNEST BILLINGTON, subjects of the King of the United Kingdom of Great Britain and Ireland, and both residing at The Linotype and Machinery Works, Broadheath, in the county of Chester, England, have invented new and useful Improvements in Typographical Composing and Casting 10 Machines, of which the following is a specification.

This invention relates to typographical composing and casting machines particularly those known as linotype machines, and more especially to those linotype machines which are provided with both a number of superposed magazines, and means whereby, by a single adjustment or operation on the part of the operator, an operative substitution 20 of the magazines can be effected simultaneously with a change, which, when such substitution calls for it, will cause the linotypes next cast to have a greater or less body dimension than that cast immediately before the said adjustment.

The present invention, among other things, comprises means whereby the linotype trimming knives may be automatically adjusted correspondingly with the above-named change of body dimension, and improved means for pushing upward the matrices in the magazines.

The invention may be embodied in a linotype machine provided with either a plurality of casting molds of different body dimension, as in the example illustrated in Figures 1 to 7 inclusive of the accompanying drawings, or a single mold provided with means whereby it may be readily adjusted 40 as to body dimension, as in the example illustrated in Figs. 8, 9 and 10 of the said drawings.

In these drawings, which are of a more or less diagrammatic nature and are to be taken as part of this specification and read therewith:—Fig. 1 is a sectional elevation as seen from the right-hand side of the improved machine having the above-named plurality of casting molds, and showing sufficient of the apparatus to illustrate the present invention; Fig. 2 is an elevation of part of the mechanism shown in Fig. 1, as seen from the left-hand side of that figure; Fig. 3 is a plan of part of the mold-wheel-

setting-mechanism shown in Fig. 1; Fig. 4 is a plan of the clutch mechanism shown in Fig. 2; Fig. 5 is a front view, and Fig. 6 an edge view of the mold-wheel drawn to an enlarged scale; Fig. 7 is a horizontal section on the line 7—7 of Fig. 1, through the improved linotype trimming mechanism and a portion of the mold-wheel; Fig. 8 is a sectional elevation, as seen from the right-hand side of the improved machine having the above-named single adjustable mold; Fig. 9 is an elevation of part of the mechanism shown in Fig. 8 as seen from the left-hand side of that figure; Fig. 10 is a horizontal section on the line 10—10 of Fig. 9; Fig. 11 is a vertical section taken along the axis of the clutch rod 27 Fig. 1, and Fig. 12 is a perspective view of the catch 35 of Fig. 1 removed from certain of its associated parts.

Referring particularly to Figs. 1 and 2:— 1, 2, 3, 4 and 5 represent portions of the several superposed magazines, of which there may be any desired number, and which are supported on the machine frame in any convenient manner, the means for so supporting them are omitted from the drawings because they constitute no part of the present invention.

6 represents the font keys, of which only one is shown in Fig. 1 and five in Fig. 2, but of which, it must be understood, there is one for each of the magazines on the machine. The connections of the several font keys 6 with their respective magazines being all practically alike, the following description 90 of one will apply equally well to each of them. The font key 6 is pivoted at 7 to any convenient part of the machine frame, and is located in a position convenient for manipulation by the operator. The key 6 is 95 connected, through a link 8, with one end of a bent lever 9, whose opposite end is adapted normally to maintain a pivoted spring-pressed tumbler 10 in such a position as to support a pivoted cam-carrying carriage 11 in position to keep its cam 12 out of contact with a constantly rotating roller or cylinder 13.

14 is the spring which serves to return the tumbler 10 to its normal position, and which is secured to any convenient part of the machine frame.

The cam 12 is free to rotate in its car-

riage 11 in a manner similar to those now used in connection with the escapement rods of ordinary linotype machines, and like those cams, its weight is so distributed that, 5 when the said cam is in its normal position, as shown in Fig. 1, there is a preponderance of weight which tends to turn the cam in a direction which, as regards Fig. 1, is the reverse of that followed by the hands of a 10 clock. To retain the cam in its normal position against the influence of the said weight-preponderance, an abutment or shoulder is provided on the said cam, which is adapted to engage with a stationary rib or abutment 15 15 when the cam carriage 11 is in its normal position.

The various font keys 6, and their co-operating mechanisms are arranged in groups according to the body dimensions of 20 the respective fonts, for instance, the first group of font keys may be appropriated to fonts of bourgeois body, the next group to fonts of brevier body, the next group to fonts of minion body, the next group to 25 fonts of nonpareil body, and so on; in the example illustrated, the number of such groups provided for, is six. Over all of the cam carriages appertaining to each of the said groups of font keys, there is provided a plate 16 preferably pivoted near its 30 rear edge to the machine frame, upon a pivot 17, this plate being tilted upward whenever a cam carriage of the corresponding group is raised. This plate 16 serves to 35 effect the stoppage of the mold wheel 18 at the particular part of its rotation at which a mold 19, 19^a, etc., Fig. 5, having the body dimension appropriate to the selected font, is in the ejecting position, it being here explained that the mold wheel 18 carries a 40 number of molds of different body dimensions such number corresponding with that of the above mentioned groups into which the font selecting mechanisms are divided.

45 In the example illustrated in Fig. 5 provision is made for accommodating six of the before-mentioned molds; only two of them are represented, but the slots in the mold wheel 18 for receiving the other four, bear 50 the references 19^b, 19^c, 19^d and 19^e, which are hereinafter used to refer to the molds which, in the complete working arrangement, would occupy those slots.

Each of the pivoted plates 16, through a 55 vertical rod 20, acts on a horizontal lever 21, pivoted to a stationary plate 22, which latter also serves for guiding the upper ends of the rods 20. Each of the levers 21 is, at its rear end, see particularly Fig. 3, in 60 pivotal connection with one end of another horizontal lever 23, perpendicular thereto, and whose other end is pivoted to the upper end of a suitably guided vertical bar 24 having a wedge or cam 25. Each of the cams 65 25 is free to be raised and lowered by the re-

spective lever 23 and is adapted, through devices including a clutch lever 26 and clutch rod 27, Fig. 4, to unclutch a spur wheel 28 from its driving mechanism and thereby arrest the rotary motion which the said spur wheel 28, through a pinion 29, transmits to the mold wheel 18. For instance as seen in Fig. 11 each cam 25 may be adapted to swing a respective projection 167, 168 or 169 into the path of a projection 173 upon a lever 174 pivoted at 175 in a bracket 176 fixed upon the wheel 28. The free end of the lever 174 is movable between guides 180 and the inward movement of the arms carrying the projections 167, 168 and 169 is made 80 against the action of blade springs 172. The wheel 28 is free to revolve upon a fixed hollow shaft 178 as is also the wheel 184 constantly driven from the so-called intermediate shaft. The clutch rod 27 can slide in 85 the hollow shaft 178 and carries two arms 182 furnished with coned rollers 186 which are pressed against the wheel 184 by springs 181 and 188 this wheel in turn pressing a flexible disk 184^a against the wheel 28 and 90 so clutching it. The spring 181 pressing one end of the rod 27 forces the other end against the lever 174. 191 is a fork for moving the arms 182 in the slots 183 in the shaft 178 when it is desired to unclutch the 95 wheel 184 from the wheel 28 at which time the spring 191^a will retract the lever 174. It will now be obvious that when a cam 25 is raised the respective projection, such as 169 as shown, will be protruded into the 100 path of the projection 173 and the lever 174 will be forced back by the impact of 173 against 169 thereby moving the rod 27 inward and unclutching the wheel 184 from the wheel 28. This mechanism is already 105 known and is merely given as an example of a suitable unclutching means. The upper edge of each side of the cam carriage 11 is provided with a bearing 30 adapted to receive the lower end of an arm or tine 31 of 110 a bifurcated push rod 32 whose upper end is guided in a stationary bar 33. The arms 31 are maintained in engagement with the bearings (into which they are inserted in a lateral direction) by the cam 12, which prevents any lateral motion of the said arms and is adapted to rotate between them. Overlying the upper end of each of the push rods 32 is an arm 34 offset from and suitably integral with (as shown in Fig. 12) a 115 catch 35 pivoted on a rod 36 and which normally is retained by a spring 37 in the position in which it is shown in Fig. 1, the said spring, at its respectively opposite ends, being attached to the arm 34 and to a stationary hook 37^a. Each of the arms 34 extends alongside of the forward end of a lever 38 there being provided one such lever for each of the magazines. The forward end of the lever 38 is moreover provided 120

with a hump 39 for a purpose hereinafter explained, and its extremity is beveled or inclined so as, during its descent, to press forward the catch 35 until said inclined extremity has passed the nose of the catch, which latter immediately thereafter snaps over the said lever under the influence of the spring 37, and retains it in position until the said catch is next disengaged therefrom by the ascent of the respective push rod 32. The rear end of each of the levers 38 is pivotally connected to the left-hand end of a lever 40 perpendicular thereto, see Fig. 2, this last named lever being operatively connected, through a link 41, with one arm of a bell-crank lever 42 pivoted to one side of the respective magazine 1 or 2, etc., and whose other arm is, by a link 43, operatively connected to the lower arm of a lever 44. To the upper arm of the lever 44 there is attached a spring 45 which acts thereon antagonistically to the appropriate cam 12, and the said lever is fast to one of the trunnions of a bar 46 which latter extends throughout the whole width of the mouth of the magazine and is free to be turned in bearings on the said magazine, to two different positions; in one of these two positions, as shown in connection with the four lowest magazines in Fig. 1, the bar 46 projects down in front of the magazine mouth and holds back the matrices 47 in the magazine, as shown in dotted lines in Fig. 1, so as to relieve the escapement pawls of their weight, while, in the other of such positions, as shown in Fig. 1 in connection with the fifth magazine from the bottom, it presents no obstruction to the outward passage of the matrices.

From the foregoing description it will be understood that when one of the cam carriages 11 is raised, the corresponding catch 35 will be disengaged from the respective lever 38 and the front end of the latter will also be raised under the influence of the respective spring 45, with the result that the corresponding bar 46 will be turned from its obstructive to its unobstructive position, in which latter position it will be retained by the said respective spring 45, until, as hereinafter described, it is next positively turned into its obstructive position.

The shaft 13 has rigidly secured thereto, a key or feather 48 wherever there is slidable a clutch sleeve 49 having teeth 50 with inclined faces as shown in Figs. 2 and 4, these teeth being capable of engagement with similar but oppositely-inclined teeth 51 on the left-hand side of a cam disk 52 having in its right-hand face a cam groove 53. The clutch sleeve 49 is provided with a spring-pressed plunger 54 as shown in dotted lines in Fig. 4, the inner end of which is adapted to engage with a recess in the shaft 13, so as to retain the said sleeve in the normal posi-

tion in which it is shown in the drawings, until positively moved from that position by the means next described. The clutch sleeve 49 is provided with an annular groove in which is located a collar 55 in which the clutch sleeve is free in a rotative sense, and to the upper part of which is secured a cam 56 having one face flat and radial, and in the vertical plane in which is situated the axis of the shaft 13. The other face of the cam 56, which is the cam proper, is of curvilinear form as shown in Fig. 4, and is adapted to be acted upon by a similarly curved face of a cam 57 projecting leftward from the left-hand face of the cam disk 52. This cam disk is, in a rotative sense, free of the shaft 13, whereon it is secured against axial movement by a screw 58 which, as shown in dotted lines in Fig. 2, engages with an annular groove formed in the said shaft 13. The cam disk 52 is weighted, as by the block or weight 59, Fig. 4, fast to it, so as to insure that when it is in its normal position, the rear or flat face of the cam 57 shall be situated in a radial plane slightly in advance of the radial plane containing the forward or leading face of the cam 56.

With the before mentioned cam groove 53 there engages a bowl 60 pivoted on a rod 61 whose lower end, as shown best in Fig. 1, is formed with a loop by which it is guided on the shaft 13, and whose upper end is pivoted to an arm 62 operatively fast to a bar 63 preferably of the cross-section shown in Fig. 1, and to which arm there is also attached one end of a tension spring 64, whose other end is attached to a convenient part of the machine frame. At its ends the bar 63 is provided with trunnions 65, one of which is shown in Fig. 2, and by which it is pivoted in suitable stationary bearings so that the rear edge of the said bar is free to move in a circular arc. The bar 63 overlies the forward ends of all the levers 38, and serves, when lowered, to press on the hump 39 of the particular one of such levers which had last previously been moved (as shown in dotted lines in Fig. 1) to bring the respective magazine 1 or 2, etc., into operative condition and thus depress the forward end of the said lever and thereby serving to restore the said magazine to its normal inoperative condition, that is to say, with its mouth obstructed by the corresponding bar 46; during this operation the front end of the descending lever 38, forces forward the respective catch 35 until the nose of such front end has passed the hook of the catch, at which juncture the said hook is moved rearward over the lever by the appropriate spring 37.

The before described collar 55 is provided with two diametrically opposite studs 66 by which it is pivoted in the forked and substantially vertical arm of a bell-crank lever

125
130

67 to whose other arm is pivoted the upper end of a link 68 whose lower end is pivoted to a horizontal bar 69. The horizontal bar 69 extends beneath all of the font keys 6 5 and is maintained constantly horizontal by two radius links 70 which, at their upper ends, are pivoted to it, and at their lower ends, are pivoted to the machine frame.

The before mentioned rod 61 is prevented 10 from moving laterally on one side by the cam 52, and on the other side, by the adjacent portion of a frame 71, the said rod being free to move vertically between these 15 two parts in response to the action of the cam groove 53 on the bowl 60. At the lower part of the rod 61, below the before described looped part thereof, there is provided an arm 72 projecting rearward from the said loop, and to which is pivoted the 20 upper end of a link 73, Fig. 1, whose lower end is pivoted to one arm of a bell-crank lever 74 fulcrumed to a suitable part of the machine frame and whose other arm is pivoted to the rear end of a push rod 75. The 25 forward end of the push rod 75 is forked and engages with a stud 76 which projects through a slot in the knife block 77 and connects with a plunger 78 which is free to slide forward and backward in a recess in the said 30 knife block. The rear end of the plunger 78 is "chisel" pointed and adapted to engage with serrations or rack teeth 79 in the front face of a wedge 80 such engagement being brought about by a spring 81 which, as 35 shown in dotted lines in Fig. 1, bears on the front end of the plunger. The upper and lower wedge faces of the wedge 80 (which faces do not appear in the accompanying drawings but are already well known in the 40 art) abut against screws 82 adjustable in lugs fast to the knife block 77, and the flat face of the said wedge bears against the trimming knife 83 which is constantly pressed outward against the said face by 45 springs 84. The trimming knife 83 is resiliently held to the back of the knife block 77 by means of two springs 85, only one of which is shown in the accompanying drawings, and that in dotted lines in Fig. 1, and 50 the relatively fixed trimming knife 86, Fig. 7, is, as ordinarily, secured to the vise frame 87.

The before-described arrangement of the parts 76, 78, 79, 80, 81, 82, 83, 84, 85 and 86 55 is already well known in the art and therefore needs no more detailed illustration or explanation than that herein previously given, but whereas in the existing arrangements the wedge 80 has been raised and lowered by hand, the present invention provides for the said wedge being adjusted automatically. For this purpose the wedge 80 is provided with a toothed rack 88 above the serrations 79, with which engages a spur 60 65 wheel 89 pivoted on a stud 90 fast to the

knife block 77, and to which wheel 89 a toothed pinion 91 is secured. The pinion 91 is in gear with a rack 92 fast to a slide 93 which is slotted to allow it to travel backward and forward on the stud 90, this slide 70 having attached to it one end of a spring 94 the other end of which is attached to a stud fast to the knife block 77, this spring serving to move the slide 93 rearward and through it and the toothed gearing 92, 91, 89 75 and 88 to move the wedge 80 upward. This upward movement of the wedge 80 is limited by a stop 95 fast to the knife block 77, the said stop being so situated that when the upper end of the wedge is in contact 80 therewith, the adjustable knife 83 will be at its maximum distance from the knife 86. The rear end of the slide 93 (which latter, for convenience of manufacture, is constructed in two parts) is provided with an 85 adjustable screw 96 which, by a lock-nut, is capable of being rigidly secured in any desired position of adjustment in the said slide, and at this same end, the slide is guided in its horizontal motion by a pin 97, 90 Fig. 7, fast to the knife block 77, and which engages, with a nice sliding fit, with a hole in the slide.

In the rim of the mold wheel 18 just to the outside of each of the molds 19, 19^a, 19^b, 95 etc., there is formed a recess 98, 98^a, 98^b, 98^c, 98^d or 98^e, see Fig. 5, in which is secured a block 99 preferably of steel, the operative or front faces of the several blocks varying as regards their relative distances from the 100 front surface of the mold wheel rim, this last named result being attained by either having all the recesses of the same depth and the blocks 99 of varying thickness, or the recesses of varying depth and the blocks 105 of uniform thickness. So far as this invention is concerned, the varying distances at which the front faces of the several blocks 99 are situated to the rear of the front surface of the mold wheel rim, are considered 110 as the depths of the several recesses 98, 98^a, etc., and these depths vary in a certain definite relationship to the different body dimensions of the respective molds 19, 19^a, 19^b, etc., thus, assuming the body dimensions of 115 the several molds 19, 19^a, 19^b, 19^c, 19^d and 19^e to successively increase in their order of mention, then the depth of the several recesses 98, 98^a, 98^b, 98^c, 98^d and 98^e will successively decrease in their order of mention. 120 The mold wheel rim is further provided with a series of recesses 100 which are so situated as to receive the head of the screw 96 when the mold wheel is moved forward to bring one or other of the molds 19, 19^a, etc., into metal-tight contact with the assembled line of matrices, each of these recesses 100, for this purpose, being separated from one of the recesses 98, 98^a, etc., by an angle of 125 ninety degrees, and all being deep enough to 130

avoid contacting with the end of the said screw 96.

When one of the font keys 6 is depressed for securing a change of font, and such change involves the use of a mold having a different body dimension and consequently a re-adjustment of the trimming knives, the operation of the before-described apparatus will be as follows:—The depression of the 10 said font key 6, causes a corresponding depression of the bar 69 which, through the link 68, bell-crank lever 67 and clutch 49, 50, 51, causes the cam disk 52 to rotate in the direction indicated by the arrow in Fig. 1, with 15 the result that the rod 61 is drawn down. This lowering of the rod 61 depresses the rear edge of the bar 63 and through it, the front end of the particular lever 38 which is operatively connected with the magazine 20 1, 2 or 3, etc., last in use, for example, in the case illustrated in Fig. 1, it would be the lever 38 appertaining to the magazine 5 which would be thus operated. This operation results in the bar 46 of the particular 25 magazine moving from its unobstructive, to its obstructive position, wherein it pushes the matrices upward in the magazine, away from the escapement pawls, and wherein it would afterward be retained by the engagement 30 of the corresponding catch 35 with the respective lever 38, until next released by the operator. During a later part of the rotation of the cam disk 52, the bar 63 is returned to its normal position and at or about 35 the completion of such rotation, the cam 57 on the said disk, comes into contact with the non-rotating cam 56 and thereby forces the clutch sleeve 49 out of operative connection with the cam disk 52 which then comes to 40 rest in its normal position and is retained in that position by the action of the spring 64 which for the time being holds the bowl 60 in an outwardly-directed pocket or recess in the cam groove 53, as shown in dotted 45 lines in Fig. 1. The last-named disengaging movement of the clutch sleeve 49, through the bell-crank lever 67 and link 68, also effects the raising of the horizontal bar 69 into its normal position. The depression 50 of the aforesaid font key 6, also, through the link 8 and bent lever 9 connected therewith, raises the corresponding tumbler 10 and thereby withdraws the support of the latter from the corresponding cam carriage 55 11 which thereupon descends so as to bring its cam 12 into frictional contact with the constantly rotating shaft 13. By these means the cam 12 is rotated and, after the concentric portion thereof has passed out of 60 rolling contact with the shaft 13, the cam carriage 11 is raised and lowered and, through the appropriate pivoted plate 16, rod 20, lever 21 and wedge 25, and other operatively connected parts, the mold wheel 65 is, in known manner, caused to present in the

casting position a mold of the desired body dimension.

By the descent as aforesaid, of the rod 61, and through the arm 72, link 73, bell-crank lever 74 and forked push rod, the plunger 78 is pushed forward out of engagement with the teeth 79 of the wedge 80, which thereupon, under the influence of the spring 94, acting through the slide 93, rack 92, pinion 91, spur wheel 89, and rack 88, is 75 moved to its highest position against the stop 95. The wedge 80 being thus raised, allows the adjustable trimming knife 83 to be moved by the springs 84 to its farthest position away from the companion trimming 80 knife 86, and upon the next ascent of the rod 61, the plunger 78, under the influence of its spring 81, will engage the teeth 79 and temporarily support the wedge 80 in its highest position. 85

When, after the foregoing adjustments, the mold wheel 18 is moved forward to bring the particular pre-selected mold 19, 19^a, or 19^b, etc., into metal-tight contact with the assembled line of matrices, (the proper 90 relative position of the mold wheel being secured as ordinarily by the coöperation of the usual registering pegs and sockets) one of the recesses 100 passes over the rear end of the screw 96, without in any way affecting it. After the casting has been effected and the mold wheel 18 has been retracted and makes the usual three-quarters of a rotation to the ejecting position, and is again advanced to effect, as ordinarily, the necessary coöperation of the registering pegs and 95 sockets, the rear end of the screw 96 is received in a pre-selected one of the recesses 98, 98^a, or 98^b, etc., the effective depth of which recess is such as may either have no 100 effect upon the said screw, as when the linotype to be trimmed is of the maximum body dimension, or move the said screw forward to a greater or less extent according to the 105 particular body dimension of the linotype 110 to be trimmed, as when the body dimension of the said linotype is of less than the maximum. Thus it will be seen that while, for trimming linotypes of the maximum body dimension provided for by the machine, the 115 particular recess 98, 98^a, or 98^b, etc., which, for that operation is caused to receive the rear end of the screw 96, is deep enough to insure the wedge 80 remaining in, or not being moved lower than, the elevated position 120 necessary for attaining that result, the depth of the other recesses will be more and more reduced as the body dimension of the linotypes to be trimmed becomes less, so that for the trimming of linotypes of minimum 125 body dimension it would be the shallowest of the recesses 98, 98^a, etc., which would engage with the screw 96 and move the wedge 80 to its lowest operative position, the plunger 78 being forced against the action. 130

of the spring 81 as the teeth of the rack 79 are successively moved downward past its rear end.

In the arrangement represented in Figs. 5, 8, 9, and 10 of the accompanying drawings, which is similar to that before described except in the features hereinafter particularized, a single adjustable mold is used, this mold having a body portion or base 101 rigidly secured to the mold wheel 18, and a cap or cover 102 readily adjustable nearer to, and farther from the body 101. For this latter purpose the mold cap 102 is provided on its under or inner side with two tabs 103, by which it is guided in slots or grooves 104 in the mold body 101, while, on its outer side, it is provided with two inclined or wedge surfaces 105, with which engage two corresponding wedge surfaces 106 on a slideable wedge bar 107. Two springs 108 exert a constant tendency to move the cap 102 away from the mold body 101, the movement in this direction being limited by the wedge bar 107. The wedge bar 107 is held to the mold wheel 18 by two guides 109 which admit of its being moved independently of the mold wheel in only a direction parallel with the direction of the length of the mold slot 110. At one end 30 of the mold cap 102 there is provided a lug 111 perforated to serve as a guide for a pin 112 which is fast to the adjacent end of the wedge bar 107. This pin 112 is encircled by a spring 113 which exerts a constant tendency to move the wedge bar 107 in the direction—it is upward in Fig. 9—which allows the mold cap 102 to be moved away from the mold body 101 by the springs 108. On the front face of the wedge bar 107 there 40 is provided a series of preferably as many steps 114 as there are changes required to be made in the body dimension of the mold, and these steps are adapted to engage with the screw 96 of the knife-adjusting mechanism 45 in the same manner as are the several blocks 99, the front faces of the several steps 114 being, in effect, the equivalent of the corresponding faces of the blocks 99, the "treads" or vertical faces of the said steps 50 being situated in relatively different vertical planes as are the corresponding faces of the respective blocks 99. On the back of the wedge bar 107 there is provided a serrated toothed rack 115 with which a detent 116 is 55 pressed into engagement by a spring 117 as shown in Fig. 10. The detent 116 is pivoted to lugs 118 fast to the mold wheel 18, and is provided with a tail 119 which, when the mold is in its normal or ejecting position 60 (in which it is shown in Figs. 8 and 9) is located just in front of an upstanding arm 120 fast to the push rod 75 which, through a plunger 78, serves to release a wedge 80 as and for the purpose hereinbefore described 65 in connection with the example illustrated

in Figs. 1 to 7, and the push rod 75 receives its motion through devices identical with those previously described.

Each of the cam carriages 11 of the example under review, is provided with a forwardly-extending arm, 11^a to the front end of which is pivoted the upper end of a vertical rod 121 guided near its lower end by a bar 122, and, at its lower end, adapted to bear on a lever 123 which is free to rock upon a stationary pivot or fulcrum 124. The left-hand end of the lever 123, through a pin and slot connection 125, is operatively connected with a lever 126 free to rock upon a stationary pivot 127, and a spring 128, acting on this combination of levers, tends always to maintain it in, or return it to, the position in which it is shown in Fig. 9. The left-hand end of the lever 126 is formed as a guide 129 in which a bar or slide 130 is capable of moving in a longitudinal direction from the position in which it is shown in full lines in Fig. 9, to that in which, in the same figure, it is shown in dot-and-dash lines, and vice versa, these motions being imparted to it through a lever 131 with which it is operatively connected through a pin 132, fast to the slide 130, engaging with a fork 133 on the upper end of the said lever. The lever 131 is free to rock upon a 95 stationary pivot 134 and, through a link 135, is operatively connected with an arm 136 operatively fast to the left-most of the two before-described radius links 70.

The before-described vertical rods 121 act 100 on the right-hand end of the lever 123 at different distances from the fulcrum 124, and, as they all receive the same length of vertical motion, the amplitude of angular motion of the lever 123 varies according to 105 which particular rod is operated, the left-most and rightmost of the rods 121 rocking the lever 123 through respectively the longest and the shortest arcs.

The font keys 6 are of the examples shown 110 in Figs. 8, 9, and 10 are each provided preferably with a handle 137 in place of the finger pad shown in Fig. 1, this, for enabling the operator more conveniently to apply the increased power necessitated by the additional "load" imposed by the working of the slide 130.

The mold wheel 18 of Figs. 8 and 9 having only one mold, is operated in practically the same manner as the corresponding wheel 120 of an ordinary linotype machine, that is to say it receives an angular motion of first 90 degrees from what is known as the ejecting or normal position (which is that represented in Fig. 9) to the casting position, and 125 then a further angular motion of 270 degrees onward to the ejecting position; it also receives motion in a fore-and-aft direction as ordinarily, but that has no bearing on the present invention.

When, in the last-described arrangement, one of the font keys 6 is depressed, and, as an indirect result thereof, the push rod 75 is moved forward to effect the release of the wedge 80, as in the example illustrated in Figs. 1 to 7, the upstanding arm 120, fast to the said push rod, by acting on the tail 119 of the detent 116, disengages the latter from the toothed rack 115 and thereby allows the wedge bar 107 to be raised by its spring 118, into its highest position, and the mold cap 102 to be moved by the springs 108 to its maximum distance away from the mold body 101. Upon the return movement of the push rod 75, that is to say, in a direction rightward of Fig. 8, the detent 116, under the influence of its spring 117, is again engaged with the rack 115.

The act of depressing the font key 6 as just mentioned, also depresses the horizontal bar 69, and this operation, through the lever arm 136, link 135, forked lever 131, 133, and pin 132, also effects the movement of the slide 130 from the position in which it is shown in full lines in Fig. 9 to that in which it is represented in dot-and-dash lines in that figure, in which latter position it overlies the top of the wedge bar 107.

It will be remembered in connection with the apparatus illustrated in Figs. 1 to 7, that each of the cam carriages 11 is rocked on its pivot to effect the operative substitution of one magazine for another; in the example illustrated in Figs. 8, 9, and 10 this rocking movement of the cam carriage is utilized for adjusting the mold to suit the various body dimensions called for by changes of font resulting from the said magazine-substitution. For this purpose the vertical rod 121 pivoted to the particular cam carriage which is rocked, is caused to depress the proximate end of the lever 123, and, as a consequence thereof, (through the lever 126 and slide 130) to depress the wedge bar 107, the teeth of the rack 115 meanwhile slipping past the detent 116. The extent of the depression of the wedge bar 107 varies according to which particular one of the rods 121 is depressed as before explained, and consequently the mold cap 102 is caused to approach the mold body 101, also to a varying extent, to correspondingly vary the body dimension of the mold slot 110, the detent 116, by engaging with the rack 115 at the termination of the descent of the wedge bar 107, serving to retain the latter in adjusted position. When the font key is released and the horizontal bar 69, as previously described, is caused to return to its normal elevated position, the slide 130 is withdrawn from over the wedge bar 107, by means of the forked lever 131, 133, link 135, and lever arm 136.

It will be observed that, as all the foregoing adjustments depend for their coming

into effect upon the depression of one of the font keys 6, the machine will remain in the same operative condition of adjustment until later, another of the said keys is depressed.

The before-described automatic knife adjusting mechanism, instead of being incorporated in a typographical machine provided with both a magazine selection apparatus and a mold selection apparatus, as in the example illustrated in Figs. 1 to 7 of the accompanying drawings, or a magazine selection apparatus and mold adjusting mechanism as shown in Figs. 8, 9 and 10 of the said drawings, can be incorporated in a typographical machine provided with the magazine selection apparatus independently of mold selection or adjusting mechanism. One obvious way of attaining the last-named result would be to substitute an ordinary mold for the adjustable one shown in Fig. 9, and a parallel-sided bar, for the wedge bar 107 shown in that figure, the said bar being suitably guided on the mold cap or mold carrier, and being in all other respects constructed and operated precisely as in the wedge bar hereinbefore described, and, so far as its knife-adjusting properties are concerned, fulfilling precisely the same functions.

We claim,—

1. In a typographical composing and casting machine having a plurality of magazines, a plurality of molds of relatively different body dimensions corresponding with the matrices of respective magazines, mold selective mechanism, trimming knives, and an adjustment in connection with said knives for positioning them to correspond with the dimensions of said molds; selective keys corresponding with said magazines, operative connections between said keys and the controlling devices of respective magazines, operative connection between said keys and said mold selective mechanism, and operative connection between said keys and said knife adjustment adapted to control the latter in consonance with the selection from said magazines and said molds.

2. In a typographical composing and casting machine having a plurality of magazines, trimming knives, and an adjustment in connection with said knives for positioning them to correspond with the dimensions of the matrices in different magazines; selective keys corresponding with said magazines, operative connections between said keys and the controlling devices of respective magazines, and operative connection between said keys and said knife adjustment adapted to control the latter in consonance with the selection from said magazines.

3. In a typographical composing and casting machine having a plurality of magazines, and selective keys corresponding

with said magazines; a closure for each magazine mouth, lever and link mechanism controlling each of said closures, locking means normally operative upon said mechanism to 5 retain each of said closures before the mouth of its respective magazine, releasing means in operative connection with said selective keys adapted to release said locking means upon the depression of the appropriate key, 10 automatic means operative upon said closures to remove them from the mouths of respective magazines when the corresponding key is depressed, and positive returning means in operative connection with said 15 keys adapted to return to the closed position any closure which may be open upon the initial portion of the movement of a selective key taking place.

4. In a typographical composing and casting machine comprising a mold carrier, a plurality of molds of relatively different body dimensions on said carrier, and selective keys any one of which is operative to bring an appropriate mold to operative position; trimming knives, an adjustment for 20 said knives, operative connection between said keys and said adjustment adapted to reset said knives at a maximum distance apart upon the operation of a key, and means in 25 connection with each mold adapted to be brought into operative connection with said adjustment for setting said knives in a position corresponding with the dimensions of the selected mold.

30 5. In a typographical composing and casting machine having a plurality of magazines, a plurality of molds, selective keys and operative connections between said keys and the controlling devices of said magazines; mold selective mechanism in operative connection with said keys, and trimming knife adjusting mechanism also in operative connection with said keys and adapted to automatically adjust the spacing of 35 said knives to suit the selected mold dimensions.

40 6. In a typographical composing and cast-

ing machine having a plurality of magazines, selective keys, and operative connections between said keys and the controlling devices of said magazines; a mold carrier, a mold on the carrier, an adjustment operative to alter the body dimension of said mold, and operative connection between said keys and said adjustment for altering said body dimension to conform with the selected magazine.

7. In a typographical composing and casting machine having a plurality of magazines, selective keys, and operative connections between said keys and the controlling devices of said magazines; a mold carrier, a mold on the carrier, an adjustment operative to alter the body dimension of said mold, operative connection between said keys and said adjustment for altering said body dimension to conform with selected magazine, trimming knives, an adjustment adapted to alter the spacing of said knives, and operative connection between said keys and said knife adjustment for altering said spacing to conform with the adjusted body dimension of said mold.

8. A typographical composing and casting machine having in combination selective keys, a mold carrier, a mold on said carrier, an adjustment for altering the body dimension of said mold, operative connection between each of said keys and said adjustment such that each key corresponds to a different adjustment of mold body dimension, trimming knives, an adjustment for varying the spacing of said knives, and operative connection between said keys and said knife adjustment such that each key corresponds to a different spacing of said knives.

In witness whereof we have hereunto set our hands in the presence of two witnesses.
